(57) **CLAIM**

The ornamental design for a transaction card, as shown and described.

DESCRIPTION

FIG. 1 is a front side view of a first embodiment of a transaction card showing our new design;
FIG. 2 is a back side view thereof;
FIG. 3 is a top elevational view thereof;
FIG. 4 is a bottom elevational view thereof;
FIG. 5 is a left side elevational view thereof;
FIG. 6 is a right side elevational view thereof;
FIG. 7 is a front side view of a second embodiment of a transaction card showing our new design;
FIG. 8 is a back side view thereof;
FIG. 9 is a top elevational view thereof;
FIG. 10 is a bottom elevational view thereof;
FIG. 11 is a left side elevational view thereof; and,
FIG. 12 is a right side elevational view thereof.

The broken lines in FIGS. 1 and 7 illustrate numbers on the transaction card and dividers between the numbers on the transaction card. The broken lines form no part of the claimed design.
